UNITED STATES PATENT OFFICE.

HENRY HUNTER, OF ST. LOUIS, MISSOURI, ASSIGNOR TO FULTON IRON WORKS COMPANY, OF ST. LOUIS, MISSOURI, A CORPORATION OF DELAWARE.

CANE-CRUSHING APPARATUS.

1,297,691.

Specification of Letters Patent. Patented Mar. 18, 1919.

Application filed August 19, 1918. Serial No. 250,595.

To all whom it may concern:

Be it known that I, HENRY HUNTER, a citizen of the United States of America, a resident of the city of St. Louis, State of Missouri, have invented certain new and useful Improvements in Cane-Crushing Apparatus, of which the following is a full, clear, and exact description, reference being had to the accompanying drawings, forming a part of this specification.

My invention relates to improvements in cane crushing apparatus, and more particularly to a combination of elements including an adjustable chute whereby the cane to be crushed is conducted from the rolls of one crusher or cane mill to the rolls of another crusher or cane mill. The object of the invention is to provide an apparatus of this kind wherein the chute can be adjusted to obtain the highest efficiency under different operating conditions. The position of the adjustable chute will depend upon the quantity of cane passing through the apparatus, the quality of the cane and the texture of the crushing rolls, and the chute can be easily adjusted while the apparatus is in operation, so the operator can experiment and at the same time observe the condition of the cane on the adjustable chute. The combination of elements herein shown enables the delivery of cane to be controlled very easily, and if the chute is properly adjusted the highest efficiency can be obtained without "choking" the crushing rolls at the delivery end of the chute.

Figure I is a fragmentary vertical section illustrating a cane crushing apparatus constructed in accordance with the present invention.

Fig. II is a fragmentary plan view, partly in section, the intermediate portion of the apparatus being broken away.

Fig. III is a section taken approximately on the line III-III, Fig. I.

The apparatus herein shown comprises rotatable crushing rolls 1, 2, 3 and 4, said rolls being arranged in pairs to crush the cane passing between them and one pair being in advance of and lower than the other.

The crushing rolls may be constructed in

any suitable manner and they may be driven by any suitable operating means.

The chute whereby the cane is conducted from the upper pair of rolls to the lower pair comprises upright side walls 5 secured to stationary parts of the machine by means of screws 6 passing through sleeves 7, which lie between said side walls and the stationary parts. The bottom wall of the chute comprises an upper section 8 and an adjustable under section 9, located adjacent to the lower roll 4, said adjustable under section being overlapped by and extended from the lower margin of the upper section 8. The means for adjustably securing the section 9 to the section 8 comprises bolts 10 passing through the lower margin of the upper section 8 and also through slots 12 in the adjustable under section, the heads of the bolts being preferably countersunk in the upper section. Side flanges 13, provided with slots 14, extend downwardly from the upper section 8 and lie adjacent to the side walls 5 of the chute. The bolts 15, passing through the slots 14, adjustably secure the upper section 8 to the fixed side walls 5. The upper end portion of the chute section 8 is secured by a pivot member 16, and it can be adjusted about the axis of its pivot, as will be presently described. 17 designates an auxiliary chute leading from the roll 2 to the upper portion of the chute section 8, the lower edge of said auxiliary chute being extended over the upper margin of said section 8, so that the cane may pass freely from one chute member to the other.

The means for simultaneously adjusting the chute sections 8 and 9 about the axis of the pivot 16 comprises a pair of adjusting screws 18, passing through threaded bearings 19 and having their upper ends in engagement with seats 20, the latter being secured to the chute section 8. 21 designates jam nuts mounted on the screws 18 and adapted to engage the fixed bearings 19, to lock the screws in the positions to which they are adjusted.

When the crushing apparatus is in operation the cane acted upon by the rolls 1 and 2 passes forwardly from the chute and is de-

100

livered to the crushing rolls 3 and 4. The forwardly moving cane, passing from the lower end of the chute, engages the adjacent lower roll 4 whereby it is lifted a slight distance and then conducted between the rolls 3 and 4. If the lower end of the chute is too high, or too low, the cane will not be properly delivered to the crushing rolls 3 and 4. The position of this lower end of the chute will depend upon the quantity of cane passing through the apparatus, the quality of the cane, the texture of the oils and the speed of the rolls. Therefore, an adjustment suitable for some operating conditions would not be desirable under other conditions. To obtain the most satisfactory results, the operator should be able to adjust the chute while the machine is in operation and to observe the conditions resulting from different adjustments. The lower end of the chute is separated a slight distance from the adjacent roll 4 so as to allow the juice from the cane to drop between the chute and the roll. If the distance between the chute and the roll 4 is too great, small pieces of crushed cane, known as "trash," will drop with the juice, and the vertical adjustments of the lower end of the chute should therefore be made without materially changing the distance between the lower edge of the chute and the adjacent lower roll.

In adjusting the chute, the bolts 10 and 15 are loosened and the screws 18 are rotated for the purpose of moving the chute about the axis of the pivot 16, thereby raising or lowering the lower end of the chute and changing its position relative to the roll. 4. The adjustable under section 9 is then adjusted to provide desired space between the chute and the roll 4. After the desired adjustment has been obtained the bolts 10 and 15 are tightened to firmly secure the chute sections.

I claim:

- 45 1. In a cane crushing apparatus, two pairs of crushing rolls, one pair being in advance of the other, a chute mounted between the pairs of rolls to direct the cane from the lower roll of one pair to the lower roll of the other pair, the bottom wall of said chute being adjustable vertically to enable its lower end to occupy different positions relative to the adjacent roll, and adjustable supporting means for said chute.
- 50 2. In a cane crushing apparatus, two pairs of crushing rolls, one pair being in advance of and lower than the other, a chute leading from the lower roll of one pair to the lower roll of the other pair, the bottom wall of said chute being adjustable vertically and longitudinally relative to the path of the cane so as to enable the lower end of the chute to properly coöperate with the adja-

cent lower roll under different operating conditions, and adjustable means for securing 65 said bottom wall.

3. In a cane crushing apparatus, two pairs of crushing rolls, one pair being in advance of and lower than the other, a chute leading from the lower roll of one pair to the lower 70 roll of the other pair, the bottom wall of said chute comprising an upper section and a lower section adjustably secured thereto, said lower section being adjustable toward and away from the adjacent lower roll, and 75 adjustable means whereby said upper section is supported to enable it to be adjusted vertically.

4. In a cane crushing apparatus, two pairs of crushing rolls, one pair being in advance 80 of and lower than the other, a chute leading from the lower roll of one pair to the lower roll of the other pair, a pivotal support for the upper portion of the bottom wall of said chute, and adjustable means whereby 85 the lower portion of said bottom wall is supported, said bottom wall being adjustable about the axis of said pivotal support to locate the lower edge of the chute in different positions relative to the adjacent lower roll, 90 and said adjustable means being adapted to secure the bottom wall in said different positions.

5. In a cane crushing apparatus, two pairs of crushing rolls, one pair being in advance 95 of and lower than the other, a chute leading from the lower roll of one pair to the lower roll of the other pair, the bottom wall of said chute comprising an upper section, an under section located adjacent to the 100 lower roll of the lower pair and adjustably secured to said upper section, the adjustable under section being movable toward and away from the adjacent lower roll, a pivotal support for said upper section, both of said 105 sections being movable about the axis of said pivotal support, and adjustable means for securing said upper section in different positions.

6. In a cane crushing apparatus, two pairs 110 of crushing rolls, one pair being in advance of and lower than the other, a chute leading from the lower roll of one pair to the lower roll of the other pair, the bottom wall of said chute comprising an upper section, an 115 adjustable end section located adjacent to the lower roll of the lower pair, said adjustable section being overlapped by and extended from the lower margin of the upper section, bolts passing through said lower 120 margin and also through said adjustable end section, the heads of said bolts being countersunk in said upper section and the adjustable end section being slotted to receive the bolts, slotted flanges extending downwardly 125 from the side margins of said upper section,

supports adjacent to said slotted flanges, bolts passing through the slots in said flanges and secured to said supports, a pivotal support adjacent to the upper end of said upper section, the upper section and the adjustable end section being movable about the axis of said pivotal support, and adjusting

screws mounted below said upper section to provide means for lifting the lower end of the chute.

In testimony that I claim the foregoing I hereunto affix my signature.

HENRY HURTER.
